(57) **CLAIM**

I claim the ornamental design for a net support, as shown and described.

DESCRIPTION

FIG. 1 is a side elevation of a net support of the present invention shown installed in the ground together with a separate ground-engaging stake and net pole, the portions shown in phantom being for illustrative purposes only and forming no part of my claimed design.

FIG. 2 is an enlarged scale side elevation view of the opposite side of the net support shown in FIG. 1.

FIG. 3 is a bottom plan view of FIG. 2.

FIG. 4 is a top plan view of FIG. 2.

FIG. 5 is an end elevation view from the left side of FIG. 2; and,

FIG. 6 is an end elevation view from the right side of FIG. 2.
